UNITED STATES PATENT OFFICE.

ARTHUR L. TALBOTT, OF PUEBLO, COLORADO.

CONDIMENT-RECEPACLE.

No. 836,615.

Specification of Letters Patent.

Patented Nov. 20, 1906.

Application filed August 19, 1905. Serial No. 274,875.

To all whom it may concern:

Be it known that I, ARTHUR L. TALBOTT, a citizen of the United States, residing at Pueblo, in the county of Pueblo and State of Colorado, have invented new and useful Improvements in Condiment-Receptacles, of which the following is a specification.

My invention relates to condiment-receptacles; and its primary object is to provide a novel and highly useful device of this character wherein the raising of the cover will deposit what dust accumulates thereon to the rear of and not into the receptacle, whereby the condiment may be kept in a perfectly clean state.

With the above and other objects in view the invention consists in the construction, combination, and arrangement of parts hereinafter fully described, claimed, and illustrated in the accompanying drawings, wherein—

Figure 1 is a front elevation of a condiment-receptacle constructed in accordance with my invention, and Fig. 2 is a central sectional view thereof.

Referring to the drawings by reference numerals, 1 1 indicate the sides, 2 the bottom, 3 the front end, and 4 the rear end, of the receptacle. The sides 1 1 extend upwardly above the front and rear ends of the receptacle and are inclined upwardly and rearwardly, as disclosed in Fig. 2 of the drawings. Secured between the upwardly-projecting portions of the sides 1 and in vertical alinement with the rear edges thereof is a back 5, the same being provided with an opening 6 adjacent its upper end, whereby the receptacle may be secured to a wall or other support. The back 5 extends above the sides 1 and is curved inwardly and upwardly from the sides 1, as fully disclosed in Fig. 1 of the drawings. The front end 3 is constructed preferably of glass, and the rear end 4 is inclined upwardly and inwardly to provide a space therebetween and the support. This end extends slightly above the front end 3 to permit the cover being supported in an inclined position when closed. 7 designates the cover, which is pivotally secured between the sides 1 by means of a shaft 8. The front end of the cover projects in advance of the ends 3 and is reduced to provide a handle 9, whereby to lift the cover. The rear end of the cover extends rearwardly beyond the rear face of the end 4 and to a point in vertical alinement with the rear face of the back 5.

In view of the rearward extension of the cover 7 and the inclination of the end 4 the dust accumulated on the cover will be deposited to the rear of and not into the receptacle 60 when the cover is elevated to gain access to the condiment. The pocket provided by the inclination of the end 4 is adapted for the reception of the dust, which may be removed therefrom by moving the receptacle from engagement with the wall or other support and caught on any suitable article, the inclination of the wall 4 facilitating the deposit of the dust upon the article in a manner that is apparent. 70

This receptacle may be, except for the front 3, constructed from wood, sheet metal, tin, or any other material and suitably ornamented.

From the foregoing description, taken in connection with the accompanying drawings, the construction and mode of operation of the invention will be understood without a further extended description.

Changes in the form, proportions, and minor details of construction may be made within the scope of the invention without departing from the spirit or sacrificing any of the advantages thereof.

Having thus fully described and illustrated my invention, what I claim is—

1. A condiment-holder comprising a back or suspending portion, a receptacle having its rear wall extending at an upward and forward inclination from the plane of the back 90 to a point in advance thereof, thus forming a chamber below the back gradually diminishing in depth therefrom and open at its rear side, and a pivoted cover adapted when in open position to discharge any dust that 95 may be contained thereon into said chamber.

2. A condiment-holder comprising a receptacle, and a back extending upwardly therefrom and secured to the side walls thereof, the rear wall of said receptacle being inclined upwardly and forwardly from the plane of the back to a point in advance thereof, thereby forming a chamber gradually diminishing in size from the upper to the lower end thereof, said chamber adapted to be normally closed by the wall from which the holder is supported, and a cover for closing the receptacle normally having an inclined position and pivoted on a line between the respective lower and upper ends of the back 105 and rear wall, whereby when the cover is open the pivoted portion thereof will turn 110

down into the upper end of said chamber to admit foreign articles upon the upper surface of the cover thereinto.

3. A holder of the character described comprising a back or suspending portion, a receptacle having its rear wall extending at a downward and rearward inclination from a point in advance of the lower edge of the back to the base of the receptacle and in alignment with the back and rear edges of the sides thereof, thus forming a chamber below the back gradually decreasing in depth there-

from and open at its rear side, and a cover pivoted between the back and upper end of said inclined rear wall, and adapted when in open position to discharge any dust that may be contained thereon into said chamber. 15

In testimony whereof I affix my signature in presence of two witnesses.

ARTHUR L. TALBOTT.
